US0D1041338S

(12) **United States Design Patent** (10) Patent No.: **US D1,041,338 S**
(45) Date of Patent: ** Sep. 10, 2024

(54) **ELECTRONIC PRODUCT PROTECTIVE CASE**

D972,947 S * 12/2022 Xie D10/70
D997,752 S * 9/2023 Kwon D10/74
D998,489 S * 9/2023 Long D10/104.1

(71) Applicant: **Xiaoshan Huang**, Shenzhen (CN)

* cited by examiner

(72) Inventor: **Xiaoshan Huang**, Shenzhen (CN)

Primary Examiner — George D. Kirschbaum

(**) Term: **15 Years**

(74) Attorney, Agent, or Firm — Vladimir Postnikov

(21) Appl. No.: **29/941,765**

(57) **CLAIM**

(22) Filed: **May 11, 2024**

The ornamental design for an electronic product protective case, as shown and described.

(51) LOC (14) Cl. **10-05**

(52) U.S. Cl.

USPC **D10/121**; D10/74

(58) **Field of Classification Search**

USPC D10/104.2, 70, 38, 121; D14/440
CPC G08B 13/2434; G08B 21/0291; E05B

73/0023; E05B 73/0041

DESCRIPTION

U.S. PATENT DOCUMENTS

D417,158 S * 11/1999 Krauss D10/30

D430,040 S * 8/2000 Fox D10/38

D547,679 S * 7/2007 Juhng D10/38

D846,552 S * 4/2019 Feng D10/38

D898,613 S * 10/2020 Stapleton D11/216

D933,499 S * 10/2021 Ford D10/38

FIG. 1 is a front elevation view of an electronic product protective case showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is another perspective view thereof.

The broken lines depict portions of the electronic product protective case that form no part of the claimed design.
